(57) **CLAIM**

The ornamental design for a cable tray component for building construction, as shown and described.

DESCRIPTION

FIG. 1 is a front perspective view of a cable tray component for building construction.

FIG. 2 is a front elevational view of the component shown in FIG. 1.

FIG. 3 is a rear elevational view of the component shown in FIG. 1.

FIG. 4 is a top plan view of the component shown in FIG. 1.

FIG. 5 is a bottom plan view of the component shown in FIG. 1.

FIG. 6 is a right side elevational view of the component shown in FIG. 1.

FIG. 7 is a left side elevational view of the component shown in FIG. 1.

FIG. 8 is a front perspective view of an alternative cable tray component for building construction.

FIG. 9 is a front elevational view of the component shown in FIG. 8.

FIG. 10 is a rear elevational view of the component shown in FIG. 8.

FIG. 11 is a top plan view of the component shown in FIG. 8.

FIG. 12 is a bottom plan view of the component shown in FIG. 8.

FIG. 13 is a right side elevational view of the component shown in FIG. 8; and,

FIG. 14 is a left side elevational view of the component shown in FIG. 8.

The features shown in broken line throughout FIGS. 8-14 form no part of the claimed design.
